CLAIM

The ornamental design for a shoe sole, as shown and described.

DESCRIPTION

FIG. 1 is a front view of a shoe sole showing our new design; FIG. 2 is a rear view thereof; FIG. 3 is a lateral side view thereof; and, FIG. 4 is a medial side view thereof.

The broken lines immediately adjacent the photographic area represent boundaries of the shoe sole and form no part of the claimed design. The broken lines showing the environment of the shoe sole form no part of the claimed design. Color forms no part of the claimed design.
